Specification for Design.

Patented Oct. 15, 1918.

Application filed August 22, 1917. Serial No. 187,557. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for Furniture, Casket, Interior or Exterior Decoration, of which the following is a specification, reference being had to the accompanying drawing, forming a part hereof, which is a face view of the ornamental design.

This design consists of a mass of roses and other flowers, leaves, twigs and buds surmounted by and entwined with a ribbon which forms a crest at the apex of the group

and which recedes or falls away on either side along lines extending at easy inclines or curves toward the bottom or base line, the whole having the general outline of a triangle of long base and low altitude.

I claim:

The ornamental design for furniture, casket, interior or exterior decoration, substantially as shown and described.

In testimony whereof I have hereunto signed my name at Syracuse, in the county of Onondaga and State of New York, this 29th day of June, 1917.

ADOLPH M. HOLSTEIN.
